INDIA RUBBER SPRING

Alexander Spencer, Westminster, London,
EnglandApplication November 17, 1934, Serial No. 753,540
In Great Britain October 29, 1931

23 Claims. (Cl. 213—40)

This application is filed as a continuation in part of each of my copending applications Serial Numbers 619,164, filed June 24, 1932, and 667,899, filed April 25, 1933.

5 This invention relates to India-rubber springs and more especially to India-rubber elements of the type disclosed in my aforesaid applications for assembly on rigid foundation or supporting plates. The invention also relates to units comprising such foundation or supporting plates having the India-rubber elements thereon.

10 Heretofore, India-rubber springs for buffing and draft gear and for other purposes have comprised a plurality of foundation or supporting plates assembled in series with intermediate separating plates, each supporting plate having rectangular, oval or annular frames of India rubber projecting from its opposite faces. In my Patent No. 1,890,795 there is disclosed a spring unit, 15 the India-rubber elements whereof are in the form of straight parallel bars, thereby simplifying the molds necessary for the manufacture of spring units and considerably reducing the cost of production. When bar-type spring elements 20 of the kind heretofore used are subjected to compression, the relative expansion transversely of the bar greatly exceeds the corresponding expansion in a longitudinal direction, with the result that such elements undergo greater distortion about their middle portions than at their extremities, with the result that such middle portions are subject to undue wear and distortion.

25 A feature of considerable importance in connection with parallel-sided bar elements is that under compression they attain a maximum transverse dimension approximately centrally of the major axis, diminishing towards each end of the bar, that result being produced by the considerable resistance to longitudinal flow or expansion of the center zones of the elements by the adjoining terminal ends so that the bulk of the distortion resulting from compression is fixed to 30 take place in a transverse direction, and, as aforementioned, such inherent asymmetry of bar type elements has the disadvantage that when such elements are assembled on a supporting plate a mutual support is provided only at the central portions of the bars and there is no continuous mutual support between adjacent bars which would obtain should the side walls of the 35 spring elements distort uniformly throughout the length of the bar.

40 Moreover, in spring units utilizing the parallel-sided bar elements heretofore employed, side areas of the supporting plates remain uncovered when the springs are subjected to stress, and whereall the bars are parallel-sided, there is a tendency to side movement owing to lack of stability transversely of the bars.

45 The primary object of this invention is to

overcome the aforesaid disadvantages and to provide a construction of spring device particularly adapted for buffing and draft gear in which the spring elements thereof shall have mutual support on each side for the major portion of 5 their length so that such elements may give a maximum effective resistance under a predetermined compression and so that distribution of stress throughout the body of the elements will be more uniform and undue wear at the middle 10 portions of the elements is avoided, whereby durability of the spring device is greatly enhanced.

15 The India-rubber spring elements may be of various shapes and may be of a generally rectangular form, as shown in my aforesaid application Serial No. 619,164, or of a generally sectorial form, as shown in my aforesaid application Serial No. 667,899. Whether the elements are of generally rectangular form, or of polygonal 20 form, if they are arranged adjacent one another on a foundation or supporting plate in a predetermined relation, the sides thereof, when the elements are subjected to a predetermined compression, will meet each other in a straight line 25 and provide mutual support throughout the major portion of their length.

25 Further and favorable objects will appear from the following description.

30 According to this invention, the India-rubber spring elements are waisted or reduced in the middle portion of their length to an extent insuring that the asymmetric distortion resulting from a predetermined load will cause the side walls of the bar to lie in a single plane and when 35 generally rectangular bar elements are utilized and such elements are subjected to a predetermined compression, the side walls thereof will become substantially parallel or equidistant 40 throughout their length.

45 Whether the bar elements are of generally rectangular form or are of generally sectorial form, or of polygonal form the portions thereof projecting at each face of the supporting foundation or plate may be truncated or pyramidal in form and when the elements are of generally rectangular or generally sectorial form the ends preferably are made curviform whereby chafing and deterioration of the corner portions is avoided.

50 When generally sectorial-shaped elements are used, their wider ends may be so shaped in the static condition that when the elements are subjected to a predetermined compression they will describe an arc of a circle, and if the elements are 55 arranged on a circular disk with their narrow ends adjacent, the center of the several arcs may be the center of the disk.

55 When applied to triangular—approximately equilateral—square or rectangular, pentagonal, 60

hexagonal and similar polygonal basic shapes of element, the invention provides re-entrant sides to the element, and further the elimination of the sharp angles between adjacent sides by eased curvilinear junctions as it were inside the angles, or preferably by curviform protuberances forming bosses encircling the angles which provide a greater area of support for the rubber at these locations and prevent the excessive wear and deterioration which is otherwise likely to occur, while simultaneously producing concavity in the side walls so that the equivalent re-entrant contour is obtained.

Hitherto, where circular India-rubber elements have been utilized, irrespective of the particular manner of disposition over the area of the supporting plate and irrespective of the shape of such plate, considerable wastage of available space between adjacent elements is an inherent defect of the circular form but this defect is avoided by the polygonal form made practicable by this invention, as elements of polygonal form may be arranged to intermesh in the manner of the cells of a honeycomb.

The present invention therefore also comprehends a spring unit consisting of a metal plate and re-entrant-sided polygonal elements of India-rubber at the faces of the plate so shaped and disposed relatively to one another that under a predetermined compression the juxtaposed side walls of adjacent elements mutually abut and substantially the whole effective area of the plate is covered, whereby most efficient utilization of the space available is obtained.

The invention will be described further with reference to the accompanying drawings which illustrate different embodiments of the invention and the India-rubber elements applied to a foundation plate to form spring units for the elements projecting from each face thereof.

In the drawings

Fig. 1 is a perspective view of one embodiment of an India-rubber element.

Fig. 2 is an empirical illustration showing the improved results obtained on deformation under stress resulting from reducing or waisting the central portion of a bar element of the form shown in Fig. 1.

Fig. 3 is an elevational view of a spring unit comprising a metal supporting plate having waisted bars disposed thereover in accordance with the disclosure of my copending application Serial Number 619,165, filed June 24, 1932, Patent No. 2,001,855, May 21, 1935.

Fig. 4 shows a plurality of units of the type shown in Fig. 3 assembled on a draw rod with separating metal plates between adjacent units and adapted for cushioning either buff or draw stresses.

Fig. 5 is an elevational view of a spring unit having India-rubber spring elements of generally sectorial form disposed over a circular supporting plate.

Fig. 6 is a cross sectional view on line 6-6 of Fig. 5.

Fig. 7 is a view similar to Fig. 5 showing the use of India-rubber spring elements of polygonal form.

Fig. 8 is a cross sectional view on line 8-8 of Fig. 7, and

Fig. 9 is an elevational view of a quasi-rectangular spring unit also embodying India-rubber spring elements of polygonal form.

Referring now to the drawings, and first to the embodiment of the invention shown in Figs. 1 to 4,

and more particularly to Figs. 1 and 2, it will be noted that the bars 1 which are employed as elements for India-rubber spring units, have their side walls 4 and 5 waisted or reduced so as to have a transverse width substantially less than the portions lying adjacent the ends of the element, and that the transverse dimensions of the elements progressively increase from the central portion of the elements to each end so that the major transverse dimension is in the immediate vicinity of each end.

As it has been found that in use rapid deterioration of the corner portions is caused by the high internal stress set up when the bar is distorted by compression, it is preferable to have the end faces of the bar of generally semi-circular or semi-elliptical form, as shown at 6 and 7, in which case the major transverse dimensions of the bar, indicated at 8, are located where the circular end faces 6 and 7 join the side walls.

When generally rectangular bar elements are subjected to a predetermined compression the side walls of the bar, owing to a greater resistance to flow in a longitudinal direction of the bar, will become substantially parallel to each other, as will be apparent from the dotted showing at 9 and 10 of Fig. 2.

Substantial operating advantages accrue from the use of elements having their center portions of reduced diameter, while the durability and stability of the assembled springs under compression is greatly enhanced.

Referring now more particularly to Figs. 3 and 4, it will be noted that the spring units are secured to metal or other rigid supporting plates 12 which comprise the foundation of the spring units which are assembled in series with metal separating plates 13 on a draw rod 14, pivoted to the rear of a coupler shank 15 and between followers 16 and 17 in the draft gear of a railway vehicle.

The bar elements 1 of India rubber project from each face of the supporting plate 12 and the coincident bars on opposite sides of the plate are united by India rubber passing through perforations in the plate as shown at 18.

The bars may be disposed in any usual or appropriate manner about the surface of the supporting plate 12, although maximum stability and durability will be obtained if the quadrated disposition forming the subject matter of my copending application Serial Number 619,615 is adopted. An example of such a disposition is illustrated in Fig. 3 where, as will readily be seen, the bars are disposed with their major axes normal to the adjoining edges of the supporting plate 12. As shown in this figure, each of the bars of the parallel series of bars 20 have their longitudinal axes disposed normal or at right angles to the adjacent plate edge 21, a facsimile of the parallel series 20 being disposed at the other side of the plate adjacent the edge 22 and being indicated by reference character 23. Intermediate the series 20 and 23, and adjoining the top and bottom edges 24 and 25, respectively, of the plate 12, are two additional parallel series of spring elements 26 and 27, respectively, having their longitudinal axes vertical, that is at right angles to their adjacent plate edges.

Each of the bar elements is of the waisted section shown in Figs. 1 and 2 and have the expansion characteristics there displayed, the side walls assuming the condition of parallelism under a predetermined compression, whereby maximum mutual support between adjacent elements

is obtained due to their opposed side walls coming into contact for substantially the full length of the elements when they are subjected to a predetermined compression. A functional advantage accruing from the employment of the waisted bar elements lies in the more uniform distribution of stress throughout the body of the element whereby the durability of the spring is enhanced. Particularly, the undue wear and distortion which normally occurs about the middle of parallel-sided bar elements is avoided. The disposition of the bars illustrated makes full use of the available surface of the plate 12 and assures a high degree of stability for reasons fully explained in my said copending application Serial No. 619,615.

For certain purposes, as where the supporting foundation or plate is circular, oval, etc., it is preferable that the India-rubber elements constituting the spring unit and projecting at each face of the supporting plate shall be of generally sectorial form. Figs. 5 and 6 illustrate elements of such form secured to a circular supporting plate and the unit thereby formed may be assembled in series with intervening separating plates in the same general manner as the units shown in Figs. 3 and 4 to constitute a spring for buffering and draft gear on railway vehicles or for like purposes.

In Figs. 5 and 6 the India-rubber elements 30 which are of generally sectorial form are shown as being secured to a circular supporting plate 31 having a central aperture 32 sufficiently large to receive a draw bar or the like. The generally sectorial blocks are disposed about the surface of the plate 31 so that their narrower ends are adjacent. Instead of the elements having their side walls disposed in radial planes when in the static condition, the elements, like the element shown in Figs. 1 to 4, have their central portions waisted or reduced so that their side walls assume a radial disposition when the unit is subjected to a predetermined compression applied through separating plates 33 and 34 indicated in broken lines in Fig. 6.

As is clearly shown in Fig. 6, the India-rubber elements project from each side of the supporting plates 31 and elements on opposite faces of the plate are united by rubber passing through perforations 35 in the plate. The elements 30 are of substantially uniform depth in the direction of compression and have flat compression surfaces 36 in contact with the adjacent separating plates 33 and 34.

Inasmuch as the transverse dimension of the elements adjacent their outer ends, as indicated at 38, is much greater than the transverse dimension adjacent their inner ends, as indicated at 39, the elements are formed so that their transverse dimension is not symmetrical as is the case with the waisted bar type elements shown in Figs. 1 to 4, and the elements are so formed that the maximum reduction occurs nearer their outer edge than at the middle thereof, as is indicated at 40. When the spring elements thus have their side walls asymmetrically reduced, the greater deformation under compression at the wider portions of the elements is compensated for and under predetermined compression the side walls of adjacent elements will meet each other in a straight line as indicated at 41 and thereby mutually support each other.

With sectorial blocks, as well as with gener-

ally rectangular elements, it has been found that undue wear and distortion occur at the corner portions, and accordingly, the side walls of the elements illustrated in Figs. 5 and 6 are so formed as to prevent a curvilinear outline, the junctions between the side and end walls being reduced at 42, 43 and 44 whereby such wear and deterioration is avoided.

The form assumed by the elements under compression is clearly illustrated in Fig. 5 where two of the blocks on the upper half of the plate are illustrated in this condition and it will be seen that their side walls have assumed a substantially radial disposition and mutually support each other thereover along the line 41. The disposition of the elements 30 on the supporting plate 31 as shown in Fig. 5 not only provides for maximum mutual support between adjacent elements by reason of their opposed side walls coming into contact for substantially the full length of the elements, but it also makes full use of the available surface of the plate 31 and assures a high degree of stability.

It will be understood that the extent of reduction in the transverse dimension of the elements 30 about their middle portions, and the asymmetry of the recesses thereby formed in the side walls of the elements is dependent on the degree of compression at which the side walls are required to assume a radial disposition and the angle formed by the side walls when the elements are compressed to an extent sufficient to cause them to assume a radial disposition. The side walls of the elements illustrated in Fig. 5 will reach the radial disposition and be caused to mutually support each other along the line 41 under compressions which reduce their depth by approximately fifty percent. The embodiment of sectorial elements illustrated in Fig. 5 also have their circumferential wall 45 flattened somewhat in the static condition, whereby under compression it presents a surface 46 substantially concentric with the periphery of the plate 31.

Referring more in detail to Fig. 7, the circular metal foundation or supporting plate 50 is similar to the plate 31 shown in Fig. 5 and has a central aperture 51 for the passage of a buffering or draw rod similar to that shown in Fig. 4. At each face of the plate 50 India-rubber spring elements 52 having flat compression surfaces 52' project and coincident elements at opposite faces of the plate are united by India rubber passing through perforations in the plate in the same manner as is shown in Fig. 6 in connection with the generally sectorial shaped elements. A plurality of units such as those shown in Fig. 7 are adapted to be assembled with intervening plates 33 and 34 of the same form as those shown in Fig. 6 to constitute a spring or cushion device for buffering and draft gear in railway vehicles or for other purposes and when so assembled the flat compression surfaces of the India-rubber elements will contact with the intermediate separating plates.

In Fig. 7 a unit having five India-rubber spring elements projecting from each face of the plate 50 is shown and the several elements have the same shape and size and are uniformly distributed about the plate in the same general manner as the generally sectorial elements 30 are distributed about the plate 31 in Fig. 5. However, in Figs. 7 and 8 the basic shape of the elements is triangular with the apex of the elements dis-

posed adjacent one another at or about the center of the plate.

In contradistinction to the elements shown in Fig. 5, the generally triangular elements of Fig. 7 are substantially symmetrical in form. That is, the outer side or base 53 of the triangle is substantially equal in extent to the side or radial walls 54 whereby the basic shape of the elements are equilateral triangles and more uniform distribution of stress throughout the body of the elements is obtained. For reasons already pointed out in connection with the form of elements shown in the preceding figures, the curviform junctions 55 are formed between the side walls 54 and the end wall 53 of each element at what would be the base angles if the elements were true triangles. The apex of each element adjacent the central aperture 52 is formed with a double curviform side 55. That particular shape is especially adapted to suit the form of foundation plate 50 as shown in Figs. 5 and 7 which have central circular apertures.

Like the side walls of the elements shown in the preceding figures, the side walls of the elements shown in Fig. 7 are reentrant or curved inwardly so that under a predetermined compression they will assume a substantially planar or radial disposition as indicated at 55 where the dotted line represents the form which the several elements assumed when they are subjected to a predetermined pressure applied normal to the flat compression surfaces and from the dotted line it will be noted that the form of elements shown in this figure also provide the mutual support for one another when the elements are placed under compression.

The degree of inward curvature of the side walls 54 of the elements and the radial spacing between the respective elements will be dependent on the compression at which it is desired that mutual support will take place, that condition being accelerated by arranging the juxtaposed side walls 54 of adjacent elements in closer proximity when correspondingly a small degree of inward curvature is necessary.

The outer or peripheral wall 53 of each element may or may not be made reentrant depending upon the particular form of foundation plate which is used. As shown in Fig. 7, the peripheral walls 53 are not made reentrant as a circular foundation plate provides a greater free space for distortion at the central portion of said side walls. However, when the peripheral walls are not made reentrant, it is preferable that they be so shaped that under a predetermined compression at which the juxtaposed side walls 54 come into contact with each other, as along the line 55, the peripheral walls will be substantially concentric with the circumference 56 of the plate as shown in 57. This may be accomplished by forming the peripheral side walls 53 on a radius somewhat greater than the radius of the circular plate so that those walls will be flattened relative to the circumference 56 of the plate.

The symmetrical and substantially equilateral form of the elements 52 permits each element to be united to its coincident element at the opposite face of the foundation plate 50 through three plate apertures 58, 59 and 60 disposed adjacent the inner and two outer extremities respectively of the element, and therefore widely distributed over the area thereof so as to provide a firm and secure anchorage. A further advantage of such a disposition of the unions between the coincident elements is that the plate anchorages there-

by provided are so located as to best resist the natural outward thrust occurring when the compression exceeds that at which the opposed side walls come into contact.

The formation of the elements 52 into substantially equilateral triangles also provides an effective covering of the supporting plate under the compression at which the sides of adjacent elements abut and mutually support each other as is clearly evidenced by the dotted lines shown on the upper half of the plate in Fig. 7 and from that figure it will be noted that only a very small portion of the area of the plate adjacent the central aperture 51 and adjacent the periphery 56 remains uncovered.

The adaptability of the generally sectorial form of elements shown in Fig. 5 or the quasi-triangular symmetrical elements shown in Fig. 7 to supporting plates having shapes other than circular is exemplified by the embodiment of the invention shown in Fig. 9 where a plurality of quasi or generally triangular symmetrical India-rubber elements are assembled upon a quasi-rectangular supporting plate 62 having apertures 63 and 64 for the passage of retaining or centralizing rods. It will be understood that the unit disclosed in this figure will constitute one of a plurality of such units which will be assembled in series to form a cushioning device of a buffering and draft gear of the type generally indicated in Fig. 4.

The India-rubber elements 65 shown adjacent the apertures 63 and 64 and the ends 66 of the quasi-rectangular supporting plate 62 of the same characteristic form as those shown in Figs. 7 and 8 and have inwardly curved opposed side walls 67 and inwardly curved inner walls 68 adjacent the apertures 63 and 64. However, the elements 65 differ slightly from the elements 52 shown in Fig. 7 as the outer sides 69 are also made reentrant, or inwardly curved, whereas the peripheral walls 53 of the elements shown in Figs. 7 and 8 were not made reentrant.

The elements 70, 71 and 72 disposed in alternate series along the top and bottom edges 73 and 74 of the plate 62, while retaining the general characteristics of the form of elements shown in Figs. 7 and 8, are more nearly triangular in shape as none of the apices are provided with the double curviform wall 68 which those elements and the element 65 have.

Centrally of the plate 62, between the apertures 63 and 64, a waisted bar element 75 of the form shown in Fig. 1 is secured to the plate as the space available between the two elements 71 is insufficient in the particular shape of the supporting plate 62 illustrated to accommodate a symmetrical element similar to the elements 65 and 70, 71 or 72.

Each of the elements 65, 70, 71 and 72 have three point anchorages or unions to their coincident elements at the opposite face of the plate 62 thereby insuring durability and freedom from likelihood of displacement in use.

The dotted lines shown in the upper half of Fig. 9 clearly disclose how the adjacent elements mutually abut and support each other when the India-rubber elements are subjected to a predetermined compression, and also how mutual contact takes place over substantially the whole of the juxtaposed side walls of adjacent elements to give maximum resistance to further movement under compression.

Where non-circular supporting plates having shapes other than that disclosed in Fig. 9 are

used, India rubber of other symmetrical shapes and sections may be employed which will best suit the configuration of the plate with which the elements are to be associated to form a spring unit whereby effective covering of substantially the whole of the available area of the plate under compression will be assured with maximum mutual support between the several elements, and uniform distribution of stress throughout the 10 bodies of the elements will be obtained.

Whether generally rectangular, generally sectorial, generally polygonal, or other shaped, India-rubber spring elements or bars are used, it is preferred to employ elements having waisted or 15 reduced center portions, but it will be appreciated that the invention in its broader aspect comprehends any formation of India-rubber elements which, under stress, assume a form such that, when the elements are suitably arranged 20 upon the carrying plate, the opposed side walls of adjacent elements may afford each other mutual support.

I claim:

1. An element for an India-rubber spring comprising a solid member of India rubber of substantially uniform depth in the direction of compression, said bar having substantially flat compression surfaces and having its major axis between said surfaces and substantially parallel 25 thereto, said member having portions adjacent each end of said axis of greater transverse dimension than a transverse dimension intermediate said end portions, whereby under a predetermined compression the lesser intermediate 30 transverse dimension will be caused to become at least equal to the transverse dimension of at least one of the end portions.

2. A bar element for an India-rubber spring comprising a solid bar of India-rubber of uniform depth in the direction of compression having flat compression surfaces and having its major axis between said surfaces and parallel thereto with the portion at each end of said axis of greater transverse dimension than its centre portion 40 such that under a predetermined compression the side walls of the element become substantially parallel or equidistant from each other throughout their length.

3. An India-rubber spring element comprising 50 a solid bar of India rubber having flat compression surfaces with its major axis lying between said surfaces and parallel thereto and its side walls curved inwardly in the direction of its length so that the centre portion of the element is of smaller transverse dimensions than the portions at the ends of said axis when in a static condition such that under a predetermined compression the side walls become substantially parallel or equidistant throughout their length.

4. An India-rubber spring element comprising a solid bar of India rubber having flat upper and lower compression faces and its major axis lying between said faces and parallel thereto and vertical side walls with curviform ends said side walls being inwardly curved longitudinally of the bar to reduce the transverse dimension of its centre portion below that of the end portions in a static condition such that on a predetermined compression applied through said faces the side walls become substantially parallel or equidistant from each other.

5. An India-rubber spring unit comprising a metal plate, perforations in said plate, bars of 75 India rubber moulded to opposite faces thereof,

coincident bars being united through said perforations, said bars being of uniform depth and in the static condition being of reduced transverse dimensions about their middle portions such that under a predetermined compression opposite side walls become parallel, and said bars being located in parallel juxtaposed relation so that the side walls of adjacent bars are brought into contact for substantially the whole length thereof, whereby mutual support of the bars by each other 1 is obtained.

6. An India-rubber spring unit comprising a metal plate, perforations in said plate, bars of India rubber moulded to opposite faces of said plate, coincident bars being united through said 1 perforations, said bars being of reduced transverse dimensions about their middle portions such that under a predetermined compression opposite side walls become parallel and said bars being located in groups of parallel juxtaposed bars so 2 that the side walls of adjacent bars of each group are brought into contact over substantially the whole length of such bars, whereby mutual support of the bars by each other is obtained.

7. An India-rubber spring element of general 2 sectorial form and of uniform depth in the direction of compression having flat compression surfaces, and its major axis between such surfaces and parallel thereto, with its side walls curved inwardly from the radial in the static condition 3 such that under a predetermined compression they assume substantially a radial disposition.

8. An India-rubber spring element comprising a solid block of general sectorial form and of uniform depth in the direction of compression 3 with flat compression surfaces and its major axis between such surfaces and parallel thereto, having its side walls curved inwardly from the radial in the static condition such that under a predetermined compression they assume substantially a radial disposition, and having curviform walls joining its side and end walls whereby the element presents a curviform outline and stress is more uniformly distributed throughout the body 4 of the element.

9. An India-rubber spring unit comprising a metal plate, perforations in said plate, spring elements of general sectorial form and of uniform depth in the direction of compression with flat compression surfaces and their major axes 5 between such surfaces and parallel thereto, at opposite faces of said plate, coincident elements being united through said perforations, said elements being radially disposed to juxtaposed relation on the plate and having their side walls 5 curved inwardly from the radial in the static condition such that under a predetermined compression their side walls assume substantially a radial disposition with the walls of adjacent blocks in contact, thereby providing mutual support for all elements of the unit over substantially 6 the whole length of each element.

10. An India-rubber spring element of general sectorial form having opposed compression surfaces, the sides of said element in the static condition having recesses therein, with the recesses extending further inwardly at the wider end of the element than at the narrower end, whereby upon a predetermined compression the respective side walls will assume a substantially planar disposition throughout the major portion of their length.

11. An India-rubber spring element of generally sectorial form having opposed compression surfaces, the sides of said element in the static 7

- condition having recesses therein, with the recesses extending further inwardly from the radial at the outer ends thereof than at the inner ends, whereby upon a predetermined compression the side walls assume a substantially radial disposition. 5
12. An India-rubber spring element of generally sectorial form and of substantially uniform compressibility, having substantially parallel opposed compression surfaces, the major axis of said element lying between said parallel surfaces and substantially parallel thereto, the sides of said element in the static condition having recesses therein, with the recesses extending further inwardly from the radial at the outer ends thereof than at the inner ends, whereby under a predetermined compression the side walls assume a substantially radial disposition. 10
13. An India-rubber spring element of generally sectorial form and of substantially uniform depth and compressibility, having opposed compression surfaces, the sides of said element in the static condition having recesses therein, with the recesses extending further inwardly from the radial at the outer ends thereof than at the inner ends, whereby under a predetermined compression the side walls assume a substantially radial disposition, the ends of said element being curved whereby stress is more uniformly distributed through the body of the element. 15
14. A spring unit comprising a plate, India-rubber elements of generally sectorial form carried by said plate, said elements having opposed compression surfaces, the sides of said elements in the static condition having recesses therein, with the recesses extending further inwardly at the wider end of the element than at the narrower end, whereby under a predetermined compression the respective side walls of the elements 20 will assume a substantially planar disposition throughout a major portion of their length. 30
15. A spring unit comprising a plate, India-rubber elements of generally sectorial form carried by said plate, said elements having opposed compression surfaces, the sides of said elements in the static condition having recesses therein, with the recesses extending further inwardly from the radial at the outer ends thereof than at the inner ends, whereby under a predetermined compression the side walls of the elements assume a substantially radial disposition. 40
16. A spring unit comprising a plate, India-rubber elements of generally sectorial form and of substantially uniform depth and compressibility carried by said plate, said elements having opposed compression surfaces, the sides of said elements in the static condition having recesses therein, with the recesses extending further inwardly from the radial at the outer ends thereof than at the inner ends, the ends of said elements being curved whereby the elements present a curviform outline and stress is more uniformly distributed throughout the bodies of the elements, the spacing of said elements on the plate being such that under a predetermined compression the side walls assume substantially a radial disposition with the walls of adjacent blocks in contact, thereby providing mutual support for all elements of the unit over substantially the whole length of each element. 60
17. A spring unit comprising a rigid plate having perforations therein, India-rubber elements of generally sectorial form attached to each face of the plate, coincident elements being connected by integral portions thereof extending through the perforations the elements having substantially parallel opposed compression surfaces, with the major axes of the elements lying between said surfaces and substantially parallel thereto, the sides of said elements in a static condition having recesses therein, with the recesses extending further inwardly from the radial at the outer ends thereof than at the inner ends, whereby under a predetermined compression the side walls of the elements assume substantially a radial disposition. 5
18. An India-rubber spring element comprising a substantially equilateral polygonal body of India rubber having flat compression faces and its side walls re-entrant or curved inwardly in the static condition, whereby stress is symmetrically distributed throughout the body of the element under compression and under a predetermined compression the side walls assume a sub-planar disposition. 15
19. An India-rubber spring element according to claim 18 wherein the area of support for the India rubber at the junctions between adjacent side walls is augmented by curviform protuberances simultaneously producing concavity in the side walls and preventing the excessive wear and deterioration otherwise likely to occur at the junctions therebetween. 25
20. An India-rubber spring element according to claim 18 having the basic shape of an equilateral triangle with the angles between adjacent sides eased by curvilinear junctions, whereby symmetrical distribution of stress obtains under compression. 30
21. An India-rubber spring unit comprising a metal plate having a central aperture and perforations between said central aperture and the periphery thereof, and India-rubber spring elements of generally sectorial form at opposite faces of the plate, coincident elements being united by India rubber passing through said perforations, the radial walls of said elements being so shaped in the static condition that under a predetermined compression the side walls of adjacent elements mutually contact over substantially the whole of their length, the inner ends of said elements having a double curviform contour with a part thereof reentrant to an extent which, under a predetermined compression, will cause the inner end of the elements to follow approximately the contour of said central aperture. 40
22. An India-rubber spring element comprising a bar of India-rubber moulded and vulcanized with a circumferential groove adapted to interlockingly engage a slotted supporting plate, having flat upper and lower compression faces terminating symmetrical wedge-shaped compression bodies of India rubber above and below said groove and having curviform ends and its center portion of reduced transverse dimension. 55
23. An India-rubber spring element comprising a bar of India-rubber moulded and vulcanized with a circumferential groove adapted to interlockingly engage a slotted supporting plate, having flat upper and lower substantially parallel compression faces terminating symmetrical wedge-shaped compression bodies of India rubber above and below said groove and having curviform ends and its centre portion of reduced transverse dimension. 60
